CLAIM

The ornamental design for a smart card reader, as shown and described.

DESCRIPTION

FIG. 1 is a top, front and right side perspective view of smart card reader, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a top, rear and right side perspective view thereof. The broken lines in the drawings illustrate the portions of the smart card reader, which form no part of the claimed design.
